CENTRIFUGAL DISCHARGER SHOE

Joseph Hertrich, Hamilton, Ohio, assignor to
The Western States Machine Company, Hamil-
ton, Ohio, a corporation of Utah

Application October 12, 1949, Serial No. 120,945

21 Claims. (Cl. 210—70)

1

This invention relates to new and improved shoe constructions for mechanical dischargers of the type used for removing treated solids from heavy-duty cyclical centrifugal machines.

The operation of such dischargers generally is controlled manually. The solids are held as an annular mass, sometimes a very hard one, inside a filtration screen lining the side wall of a large basket having a centrally open top. When ready to be discharged the basket is rotated slowly, say at 50 R. P. M., and the forward end of an elongated discharger shoe is then moved into the turning mass to cut first outward and then downward through the mass.

There are serious difficulties in the use of known discharger shoes, and particularly so when discharging very finely divided coherent solids, such as fine grained dextrose or sugar, after treatment in high speed centrifugal machines.

The discharger shoe too frequently damages or rips out the basket lining, causing heavy expense for screen replacements as well as costly interruptions of centrifugal work. Stops generally are provided on the shoe operating mechanism to prevent movement of the shoe tip beyond the face of the screen, but stops are not always effective. Sometimes they are not set properly. Sometimes the pressure of rotating solids against the shoe produces enough elastic deflection in the mechanism to render the stops ineffective. Sometimes the basket itself swings its screens into the shoe tip in reaction to that pressure.

A high degree of skill and care is required to minimize these troubles, yet conditions exist in the use of known shoe constructions which even the most skillful operators may not be able to control. For one thing, when the shoe is working at the basket screen the full thickness of the mass of solids may bear against it to thrust its tip toward the screen with a force that varies with the hardness of the mass, the depth of cutting of the shoe and the speed or torque of the rotating basket. Though a flexible cutting tip be used according to the Roberts U. S. Patent No. 2,076,516, the pressure of the rotating solids may still thrust it into the screen. Another factor is that the usual shoe wedges solids rotating against its face laterally inward against the resistance of inward portions of the mass, and this makes it more difficult to control the shoe position.

Difficulty arises also in entering the discharger shoe into a hard mass of solids and in controlling its cutting depth as it is moved outward toward the basket screen. Though the shoe may pene-

2

trate the face of the mass, if the operator thrusts it too far in or if the basket is rotating too fast he may lose control of its position under the resulting high pressure, and damage may result. If the face of the mass strongly resists penetration by the shoe tip, the operator sometimes slams or otherwise forces it in while the basket rotates so strongly that uncontrolled outward shoe movement and damage may follow.

Occurrences of the sort mentioned not only may damage basket screens but also are liable to bend or break the discharger, and occasionally even the basket shaft or the basket itself is damaged or wrecked.

Another practical difficulty exists in the hazard of the discharger shoe being moved inadvertently into working position while the basket is spinning at high speed, which would cause serious wreckage or injury. To avoid this dischargers are generally held entirely outside the basket on the top of its surrounding curb during spinning periods. It results that automatic discharger operation is generally avoided in the use of known shoe constructions in normal ways, because the automatic operating mechanisms which would be required for moving the shoe and controlling its movements both inside and outside the basket are too complicated for practical use.

A general object of the present invention is to provide discharger shoe constructions which overcome or largely alleviate difficulties encountered in the use of known centrifugal discharger shoes.

A more particular object is to make the functioning of dischargers reliable and less hazardous than heretofore, so that injuries to workmen, damage to basket screens, dischargers or other machinery, and interruptions of centrifugal work may be avoided.

Another object is to make it possible to discharge centrifugals safely and efficiently without requiring a high degree of human attention and skill.

And another object is to provide discharger shoes which can be held inside the centrifugal basket at all times without danger of wrecking the machine, so that practical automatic mechanisms may be used with safety to operate the dischargers, if desired.

According to an important feature of this invention, a discharger shoe having an elongated shoe body of suitable form is provided with two cutting or digging tips at its forward end so that a double discharging action is obtained as the shoe works near the basket screen. The two tips

are aligned laterally and spaced apart to act at different radial distances from the axis of the basket. The outer tip, however, is mounted for movement inward relative to the shoe body under pressure, and is normally held yieldably at its outer position by a force insufficient to dig it into the screen. The inner tip preferably is rigid with the shoe body and leads solids moving inside its line of action over the face of that body.

It results that most of the solids displaced by the shoe as it works along the basket screen are engaged and deflected by the inner tip and the face of the shoe body, which bear the main pressure of the rotating mass, while the outer tip which lies at the screen cuts out a swath of solids not thicker than the radial distance between the two tips. That distance may be selected so that only a limited pressure can be exerted by the rotating solids against the outer tip. Furthermore, the outer tip moves inward under pressure exceeding the force above mentioned, thus protecting the basket screen against injury; and it can be arranged so that pressure from the thin layer of solids it displaces will not thrust it into the screen.

In a preferred embodiment, the inner tip is the leading edge of the shoe body and the outer tip is carried on an arm pivoted to the forward end of the shoe body and extending backward and outward from it at its outer side, the arm being normally held in outer position by a spring supported on the shoe body. In another embodiment the outer tip is located on a pivotal arm at the leading end of the shoe body so as to extend forward and outward from that end and deflect solids over the shoe face, while the inner tip is spaced ahead of the outer tip on a rigid forward extension of the shoe body.

According to another feature of the invention, it has been found that the depth of action of a discharger shoe in a rotating mass of solids can be controlled mechanically at the shoe itself by providing the shoe body with an outward-facing skid surface to ride on part of the rotating mass at a certain distance inward from the outermost cutting edge of the shoe. When the depth of the swath being cut by that edge tends to exceed the radial distance between it and the skid surface, pressure of the rotating solids against that surface holds the shoe against further movement into the mass, or even ejects it from too deep a position, thereby limiting the cutting depth.

A double-cutting shoe as here disclosed may be provided with such a skid surface extending laterally backward and outward from a point near the inner cutting tip in alignment with upper portions only of the two tips. The outward cutting movement of such a shoe is limited, per basket revolution, to not more than the radial distance existing between the edge of the outer tip and the skid surface, during which movement only the outer tip is active; while on downward movement both tips displace solids and the deepest swath cut per basket revolution is determined by the tip height below the skid surface. When the shoe tends to cut deeper in either direction part of the solids rotating in the basket will engage the skid surface to prevent deeper cutting action.

Furthermore, when such a shoe works at the basket screen under pressure sufficient to move the outer cutting tip inward, the skid surface will slide against the screen and protect it from being gouged by the inner cutting tip. Operation

especially free from screen abrasion can be obtained under these conditions by making the skid surface and the outer tip of a hard synthetic resin material, which has been found to exert 5 remarkably little friction in sliding contact with basket screens. For this purpose pieces of hard laminated phenol-aldehyde or urea-aldehyde resin may be used; for example, the material known as "Formica."

10 A double-cutting shoe provided with a skid surface as here disclosed may be used with such a limited force on the movable outer tip that the shoe could not enter the face of a mass of sugar spinning at high speed in the centrifugal 15 basket, or could cut so little as to cause no damage. Such a shoe therefore can be kept safely inside a centrifugal basket at all times and affords a means for making a simple yet safe 20 automatically discharged cyclical centrifugal machine.

According to a further feature of this invention, easier discharging action and an advantageous deflection of displaced solids can be obtained by making the discharger shoe as an elongated arcuate body having a cutting tip at the leading edge, a cutting edge along the bottom and a facial concavity extending upward from the bottom edge in the forward portion of the shoe face. The concavity proceeds from outward 25 curvature in the lower forward face portion into inward curvature in the upper forward face portion; the latter preferably continuing into and along the upper backward face portion while the former merges into a lower backward face portion 30 substantially parallel to the axis of movement of the shoe. The tip at the leading edge of such a shoe body may be formed advantageously as an intersection of the forward concavity by a surface fitting the side wall of the basket. Thus it has forwardly projecting bottom 35 and top points with backwardly curved edges converging between them, yet it works near the basket screen in substantially parallel relation to the face of the screen.

45 With a construction of this kind, the solids displaced by the shoe body pass freely from its cutting edges into its facial concavity and are then deflected upward and showered inward toward the basket axis.

50 Discharger shoes of the type described may be adapted to enter readily into very hard masses of 55 rotating solids by providing them with digging devices in position to work only as a hard mass is being entered by outward shoe movement. If the shoe body has a flexible cutting tip leading to its face, a rigid digging device may project from the outer side of the shoe body at a location spaced well backward from the tip. In a 60 double-cutting shoe having a backwardly disposed flexible cutting tip, the outer tip itself may serve as such a digging device by providing means to stop its yielding inward movement, as it enters a hard mass to be discharged, at a point where it still extends beyond the radial position of the 65 inner tip on the shoe body.

The foregoing and other objects, features and 70 advantages of this invention will become apparent from the following detailed description and the accompanying drawings of illustrative embodiments.

In the drawings:

Fig. 1 is a view partly in plan and partly in horizontal cross section of an assembly of a preferred discharger shoe construction with a centrifugal basket and a suitable discharger operat-

ing mechanism on the basket curb. The shoe is here shown at an intermediate position of outward movement into a mass of solids rotating in the basket.

Fig. 2 is an enlarged view showing the shoe of Fig. 1 as it may work at the basket screen;

Fig. 3 is a perspective view of the shoe shown in Figs. 1 and 2, looking toward its outer side from a point ahead of its forward end;

Fig. 4 is another perspective view of the same shoe, looking toward its inner side from a point in line with its inner tip;

Fig. 5 is an elevation of the forward portion and part of the backward portion of the inner face of the shoe body, as viewed from line 5—5 of Fig. 2;

Fig. 6 is a sectional outline of the shoe taken at line 6—6 of Fig. 2;

Fig. 7 is a sectional outline taken at line 7—7 of Fig. 3;

Fig. 8 is a sectional outline taken at line 8—8 of Fig. 3, with part of the upper shield structure broken away;

Fig. 9 is a perspective view of the forward part of another embodiment of the invention;

Fig. 10 is a plan view of the shoe of Fig. 9 in position to enter a mass of solids in a rotating basket, the basket and its contents being shown in horizontal cross section;

Fig. 11 is a view similar to Fig. 10 but showing the shoe at an intermediate position of its outward movement;

Fig. 12 is a similar view indicating the action of the shoe at the basket screen; and

Fig. 13 is a fragmentary perspective view of the forward part of the same shoe, looking at its inner side from a point above and ahead of its inner tip.

Referring to the drawings:

Fig. 1 indicates a centrifugal basket 1 suspended in usual manner on a gyratory vertical spindle 2 for rotation about its axis A. The basket has a bottom 3 and a centrally open cap or top 4. They embrace its cylindrical side wall which comprises a strong perforated shell 5 and foraminous linings 6 that form a filtration screen. A stationary curb 7 surrounds the basket. The basket is shown rotating in clockwise direction with an annular mass or wall 8 of solids in its being discharged by outward movement of the discharger shoe 10. As the solids are discharged they may fall through openings 3a in the basket bottom.

The movements of shoe 10 are brought about through an operating mechanism 12 fixed to the curb top. This mechanism embodies features disclosed in my copending application, Serial No. 712,781, filed November 29, 1946, now Patent Number 2,628,719, but any other suitable mechanism may be used. For present purposes, it is sufficient to mention that the shoe 10 has a base 11 at its backward end fixed to a shaft 13 which is slidable vertically but held against rotation in a guide passage of a housing 14 that is swingable horizontally about a fixed vertical axis at B on the curb top. A handle 15 extends from housing 14 and can be manipulated by an operator to swing the housing, shaft 13 and shoe 10 inward and outward relative to the basket axis. A hand wheel 16 connects through housing 14 with a pinion 17 engaging a gear rack on shaft 13, so that the operator may move the shoe vertically by turning the hand wheel.

Essentially, the shoe 10 need only be movable horizontally so as to swing its forward end 21

out to and inward from the basket side wall, and vertically so as to move it down and up in the basket. A discharging operation may be effected, as is customary, by swinging it outward through a layer of the mass 8 just below top 4 and then moving it downward along the face of screen 6 to bottom 3, or by moving the shoe part way outward at the top, then downward, and then farther outward at the top and downward again.

The shoe 10 extends forward from base 11 as an elongated arcuate body 20 which can lie entirely inside the opening of basket top 4 and can have its forward end 21 swung outward to the face of screen 6 as seen in Fig. 2. A shield structure 22 of known nature extends upward from the back of body 20 to keep solids away from the discharger shaft. The body presents an arcuate face 50 formed to deflect solids toward the basket outlets 3a, as described more fully below.

The forward end of the shoe body carries two laterally spaced cutting tips 23 and 24. Tip 23 is the leading edge of the shoe body. Tip 24 is formed by a blade member 25 held on the outer end 26 of a pivotal arm 27, which extends backward and outward from body end 21. The inner end of arm 27 carries a pivot pin 28 fitting into a socket in the shoe body, and the arm is held in the socket by head 29 of a screw threaded into that end (Fig. 6).

Thus the arm 27 and cutting tip 24 thereon are swingable laterally relative to the outer side of the shoe body. They have an outer position at which a pin 30 on the arm abuts against an opposing projection 31 from end 21. At this position movable tip 24 lies at a greater radial distance from the axis of the basket than the fixed tip 23 on the shoe body. A leaf spring set 32 is supported on the top surface 33 of the shoe body and bears at its free end 34 against a part 35 of arm 27, thus holding the arm and its tip yieldably at the described outer position. The leaf springs 32 bear between their ends against a fulcrum on body 20 at 36, and their backward end 37 is engaged by a set screw 38 which is threaded through a backward part of the shoe body and can be adjusted in position to select a desired spring force.

The spring force is set at a magnitude insufficient to dig the outer cutting tip 24 into the basket screen. This tip yields and moves inward relative to the shoe body whenever pressure exerted against it exceeds the spring force normally holding it in outer position.

Between the two tips 23 and 24 and in lateral alignment only with upper portions of their cutting edges, the forward end of the shoe body carries a portion 40 extending outward and backward from the region of inner tip 23. The abutment 31 for stop pin 30 on arm 27 is conveniently an inner part of this extension. The forward side of extension 40 is faced with a layer 41 of a hard synthetic resin material, such as "Formica," which presents a surface 42 serving as a skid to limit the depth of action of the shoe in the rotating mass of solids. The skid surface begins at a point near the upper portion of the inner cutting tip 23 and extends laterally outward and backward with a curvature approximating though sharper than that of the basket side wall, and it is spaced inward toward the basket axis from the normal position of the outer cutting tip 24 so that a limited thickness of rotating

solids may pass outside surface 42 to be discharged by tip 24.

The blade member 25 which forms the outer tip, like the skid surface, is preferably a piece of a hard synthetic resin material such as "Formica". This may be held in place by channels 25a on the outer end of arm 21.

The inner cutting tip 23 in this embodiment acts principally during the downward discharging movements of shoe 10, although it might act during outward movements also in the absence of the skid surface. The shoe face 50 extends backward from tip 23 above a long cutting edge 51 at the bottom, and any solids rotating inside these two edges are displaced so as to pass over face 50 and be deflected efficiently by it toward the center of the basket. For the latter purpose, the forward portion of face 50 extends upward from the bottom cutting edge in a concave form composed of an outwardly curved lower forward face portion 52 and a merging inwardly curved upper forward face portion 53. The cutting tip 23 is formed as an intersection of these curved surfaces by a surface fitting the basket side wall. Tip 23 therefore works near screen 6 in a vertical plane substantially parallel to the screen, as will be evident from its appearance in Fig. 4, and it possesses a complex outline comprising forwardly projecting points 54 and 55 at bottom and top with backwardly curving convergent edges 56 and 57 between these points. See Fig. 5.

As indicated further in Figs. 4, 7 and 8, the upwardly inward curvature of the upper forward face portion 53 continues into and along the upper backward portion 53a of the shoe face. On the other hand, the upwardly outward curvature of the lower face portion 52 merges along the shoe into a lower backward face portion 52a which is substantially vertical, i. e., parallel to the axis of shoe movement. See Fig. 8. Fig. 7 shows a sectional outline of the shoe body at an intermediate place where its lower face portion has begun to straighten vertically.

In order to facilitate entrance of the discharger shoe into the face 9 of a hard mass of solids, the arm 21 may carry a stop member 58 aligned with an abutment 59 on the outer side of the shoe body. If the solids at 9 resist penetration by tip 24 strongly enough to overcome the force of spring 32, arm 21 may flex inward until parts 58 and 59 abut to hold the tip rigid. At this point tip 24 still lies radially outside tip 23. Entrance into the face of the mass then may be effected by applying increased outward force to the shoe.

The operation of this preferred embodiment will be evident from what has been described but may be summarized as follows:

With the basket 1 rotating slowly, say at 50 R. P. M., the forward end of the shoe is first swung outward into the top of the mass of solids, and entrance into the mass is effected by action of the outer tip 24 which either enters immediately or flexes inward to become rigid and then enter in the manner just described. As the shoe is moved further outward toward the basket screen a top layer of the rotating solids is removed against tip 24, which deflects the solids inward at the back of the shoe body. In each basket revolution tip 24 cuts out a swath limited in thickness to not more than the radial distance existing between its edge and the skid surface 42. As diagrammed in Fig. 1, the face 8a of the rotating mass, from which a swath was last removed, firmly supports the skid surface while the outer tip is removing another swath. The shoe there-

fore cannot be inserted too fast or too deeply into the charge.

When the shoe reaches the basket screen only a thin layer of solids, as indicated at 8b in Fig. 2, may remain to be scraped from the screen by the outer cutting tip. If stops 18 and 19 on the discharger mechanism (Fig. 1) have not stopped the shoe with tip 24 exactly at the screen, this tip may engage the screen and flex inward against the force of spring 32, as diagrammed in Fig. 2, without causing damage to the screen. The thin layer of solids rotating against tip 24 does not cause it to dig into the screen. And if it flexes inward under heavy enough pressure, the skid surface 42 will engage and slide on the screen to keep the rigid inner tip 23 from digging into the screen.

A top layer having been removed, the shoe 10 next is moved downward in the rotating mass. In this movement most of the thickness of mass 8 is displaced over the face of the shoe body by action of its cutting tip 23 and its bottom cutting edge 51; so the shoe body bears the main pressure of the mass. The flexible outer tip 24 continues, however, to act on a thin layer of solids at the face of the screen as it did when reaching the screen on the outward shoe movement, its work being confined to the removal of solids left between inner tip 23 and the face of the screen. And the depth of cutting per basket revolution continues to be limited by the skid surface 42, for if the shoe cuts deeper than the height between point 54 and the bottom of skid 42, the skid will be engaged by part of the rotating mass to thrust the shoe away from its working position.

The solids displaced along the cutting edges of face 50 move freely into its forward concavity over the upwardly outwardly curved lower surface 52 and are deflected upward and then inward by the upwardly inwardly curved upper surface 53-53a, which showers them toward the basket bottom openings 3a.

Referring now to the second illustrative embodiment of Figs. 9 to 13, these show the forward portion of a modified conventional shoe body 100 which has been provided according to the present invention with double cutting tips 103 and 110, with a skid surface 114 between them, and with a special form of digging device disposed backward from the outer cutting tip at 120.

The shoe body again is an elongated arcuate member, but here it has an inner face 102 of known form. A flexible cutting tip 103 is carried at its leading end 104 but extends forward and outward from this end to deflect solids to its face. Tip 103 is on the free end of a movable arm 105 that reaches backward along the outer side of the shoe body to a fulcrum pin 106, beyond which the backward arm end 107 is held under tension by a spring 108. The spring 108 thus holds tip 103 yieldably in an outward position. Its normal location is determined by a stop pin 109, but it can move inward relative to the shoe body under pressure exceeding the force of the spring.

The other cutting tip 110 is provided ahead of the flexible tip 103 on a rigid member 111 which extends forward from the top of the shoe body and presents an inner surface 112 leading to the shoe face 102. Tip 110 is the leading edge of surface 112 and is disposed at a shorter radial distance from the basket axis than the edge of tip 103.

The skid surface 114 is provided on a part of member 111 which extends outward and backward from an upper portion of the inner cutting tip 110. Again, the skid surface is formed with

a curvature approximating that of the rotating mass of solids and is spaced radially inward from the normal position of the outer cutting tip.

At a position well behind outer tip 103 the outer side of the shoe body carries a digging device consisting of two rigid projections 120 which terminate in blades lying transverse to the axis of shoe movement. These blades extend to a radial position about as far as that of the edge of tip 103 when the shoe is in position to enter the face 9 of a mass of solids in the centrifugal basket. Accordingly, if the mass resists penetration strongly enough to move tip 103 inward against the force of spring 108, the blades 120 will break into the face of the rotating solids as diagrammed in Fig. 10. Then tip 103 comes into action.

As outward movement of shoe 100 continues the flexible outer tip 103 works to displace successive swaths of solids limited in thickness by the radial distance between its leading edge and the skid surface 114. The action is diagrammed in Fig. 11 and proceeds substantially as described in connection with the first embodiment, except that the displaced solids pass over the shoe face 102 instead of being deflected back of the shoe as in Fig. 1.

When the outer tip 103 reaches the basket screen it works there in much the same way as the outer tip of the first embodiment, as diagrammed in Fig. 12. In this case, however, tip 103 preferably is made with a blunt leading edge 115 so that pressure of solids rotating against this edge will tend to move it inward and thus counteract the opposite tendency of solids moving against its inner face.

During downward movement of shoe 100 along the basket screen, the bulk of the rotating solids is displaced inside the fixed inner tip 110 over the surfaces 112 and 102, while the flexible outer tip continues to displace only a limited layer of solids moving between tip 110 and the basket screen. As previously described, the skid surface 114 positively prevents tip 110 from pressing into the screen. The rate of downward cutting is limited by action of the skid surface in substantially the manner described in connection with the first embodiment.

It will be evident that the new features here disclosed and claimed may be embodied in various forms of centrifugal discharger shoes differing from the illustrative forms described above.

What I claim is:

1. In a centrifugal discharger including a discharger shaft to extend into a centrifugal basket and an elongated shoe projecting radially from the shaft, the shaft and shoe being adapted to be turned about a fixed axis substantially parallel to the basket axis in the same angular sense as the sense of basket rotation so as to swing the shoe outward through solids rotating in the basket, and then to be moved downward in the basket through such solids, a discharger shoe body, two laterally aligned solids discharging tips at and carried by the leading end of said body, one of said tips being at a greater radial distance than the other from the basket axis throughout the path of swinging movement of the shoe, so that said one tip leads the shoe into the rotating solids during its outward swinging movement and both tips discharge swaths of solids during its downward movement.

2. In a centrifugal discharger including a discharger shaft to extend into a centrifugal basket and an elongated shoe projecting radially from the shaft, the shaft and shoe being adapted to be

turned about a fixed axis substantially parallel to the basket axis in the same angular sense as the sense of basket rotation so as to swing the shoe outward through solids rotating in the basket, and then to be moved downward in the basket through such solids, a discharger shoe body, two laterally aligned solids discharging tips at and carried by the leading end of said body, one of said tips being at a greater radial distance than the other from the basket axis throughout the path of swinging movement of the shoe, so that said one tip leads the shoe into the rotating solids during its outward swinging movement and both tips discharge swaths of solids during its downward movement, and means yieldably mounting said one tip and that it is movable inward relative to said body against said yieldable means under excessive basket pressure.

3. In a centrifugal discharger including a discharger shaft to extend into a centrifugal basket and an elongated shoe projecting radially from the shaft, the shaft and shoe being adapted to be turned about a fixed axis substantially parallel to the basket axis in the same angular sense as the sense of basket rotation so as to swing the shoe outward through solids rotating in the basket, and then to be moved downward in the basket through such solids, a discharger shoe body, two laterally aligned solids discharging tips at and carried by the leading end of said body, one of said tips being at a greater radial distance than the other from the basket axis throughout the path of swinging movement of the shoe, so that said one tip leads the shoe into the rotating solids during its outward swinging movement and both tips discharge swaths of solids during its downward movement, and means yieldably mounting said one tip so that it is movable inward relative to said body against said yieldable means under excessive basket pressure, the other of said tips being fixed relative to said body in position to lead solids over the inner face of said body.

4. In a centrifugal discharger including a discharger shaft to extend into a centrifugal basket and an elongated shoe projecting radially from the shaft, the shaft and shoe being adapted to be turned about a fixed axis substantially parallel to the basket axis in the same angular sense as the sense of basket rotation so as to swing the shoe outward through solids rotating in the basket, and then to be moved downward in the basket through such solids, a discharger shoe body, two laterally aligned solids discharging tips at and carried by the leading end of said body, one of said tips being at a greater radial distance than the other from the basket axis throughout the path of swinging movement of the shoe, so that said one tip leads the shoe into the rotating solids during its outward swinging movement and both tips discharge swaths of solids during its downward movement, and means yieldably mounting said one tip so that it is movable inward relative to said body under excessive basket pressure, the other of said tips being fixed relative to said body in a position to lead solids over the inner face of said body, and a lateral passageway between said one tip and the outer side of said body for the free escape therebetween of solids discharged by said one tip.

5. In a centrifugal discharger including a discharger shaft to extend into a centrifugal basket and an elongated shoe projecting radially from the shaft, the shaft and shoe being adapted to be turned about a fixed axis substantially parallel

11

to the basket axis in the same angular sense as the sense of basket rotation so as to swing the shoe outward through solids rotating in the basket, and then to be moved downward in the basket through such solids, a discharger shoe body, two laterally aligned solids discharging tips at the leading end of said body, and means for holding one of said tips at a greater radial distance than the other from the basket axis throughout the path of swinging movement of the shoe, so that said one tip leads the shoe into the rotating solids during its outward swinging movement and both tips discharge swaths of solids during its downward movement, said holding means comprising an arm swingable relative to said body on an axis substantially parallel to the axis of shoe movement, said one tip being on the free end of said arm, and spring means biasing said arm to an outermost position.

6. In a centrifugal discharger including a discharger shaft to extend into a centrifugal basket and an elongated shoe projecting radially from the shaft, the shaft and shoe being adapted to be turned about a fixed axis substantially parallel to the basket axis in the same angular sense as the sense of basket rotation so as to swing the shoe outward through solids rotating in the basket, and then to be moved downward in the basket through such solids, a discharger shoe body, two laterally aligned solids discharging tips at the leading end of said body, and means for holding one of said tips at a greater radial distance than the other from the basket axis throughout the path of swinging movement of the shoe, so that said one tip leads the shoe into the rotating solids during its outward swinging movement and both tips discharge swaths of solids during its downward movement, said holding means comprising an arm swingable relative to said body on an axis substantially parallel to the axis of shoe movement, said one tip being on the free end of said arm, and spring means biasing said arm to an outermost position, said spring means including a leaf spring bearing at one end against said arm and at the other end against an abutment fixed relative to said body.

7. In a centrifugal discharger including a discharger shaft to extend into a centrifugal basket and an elongated shoe projecting radially from the shaft, the shaft and shoe being adapted to be turned about a fixed axis substantially parallel to the basket axis in the same angular sense as the sense of basket rotation so as to swing the shoe outward through solids rotating in the basket, and then to be moved downward in the basket through such solids, a discharger shoe body, two laterally aligned solids discharging tips at the leading end of said body, and means for holding one of said tips at a greater radial distance than the other from the basket axis throughout the path of swinging movement of the shoe, so that said one tip leads the shoe into the rotating solids during its outward swinging movement and both tips discharge swaths of solids during its downward movement, said holding means comprising an arm swingable relative to said body on an axis substantially parallel to the axis of shoe movement, said one tip being on the free end of said arm, and spring means biasing said arm to an outermost position, said arm being pivoted to and extending backward from a forward part of said body.

8. A centrifugal discharger as described in claim 7, and cooperative means on said body and said arm for stopping inward relative movement

12

of said arm at a position where said one tip thereon is still outside said other tip.

9. A discharger shoe for removing solids from a rotating centrifugal basket lined with a filtration screen, comprising an elongated shoe body carrying at its forward end two laterally aligned spaced cutting tips, one tip being normally disposed outside the other to act at a greater radial distance from the axis of the basket and being movable inward relative to said body under pressure, and an outwardly facing skid carried by said body between the two tips and having its working surface in lateral alignment with upper portions only of said tips and spaced radially inward from the normal position of the leading edge of the outer tip for limiting the rate of discharging by riding on part of the rotating solids.

20 10. A discharger shoe as described in claim 9, said inner tip being the leading edge of the shoe body and said skid having its surface extending backward and outward on a part of said body from a point near said edge.

11. A discharger shoe as described in claim 10, said outer tip being movable inward under pressure to a position where said skid may slide on said screen.

12. A discharger shoe as described in claim 11, the working surface of said skid being composed of a hard synthetic resin material to limit its friction in contact with said screen.

13. A discharger shoe for removing solids from a rotating centrifugal basket, comprising an elongated arcuate shoe body adapted to be swung outward into solids rotating in the basket and then lowered into such solids, said body having a longitudinally concave inner face for deflecting solids, a cutting tip presenting an upwardly extending cutting edge along the leading and edge of said face, said cutting edge lying substantially parallel to the basket side wall when the shoe is at its outmost position adjacent thereto, and a substantially straight-concave cutting edge along the bottom of said face, the forward portion of said face being curved concavely upward from said bottom cutting edge with upwardly outward curvature in the lower portion merging into upwardly inward curvature in the upper portion.

14. A discharger shoe as described in claim 13, the upwardly inward curvature continuing into and along the backward upper portion of said face and the upwardly outward curvature merging along said face into a backward lower face portion substantially parallel to the axis of movement of the shoe.

15. A discharger shoe for removing solids from a rotating centrifugal basket, comprising an elongated arcuate shoe body adapted to be swung outward into solids rotating in the basket and then lowered into such solids, said body having a longitudinally concave inner face for deflecting solids, a cutting tip presenting an upwardly extending cutting edge along the leading and edge on said face, said cutting edge lying substantially parallel to the basket side wall when the shoe is at its outmost position adjacent thereto, and a substantially straight-concave cutting edge along its bottom, the forward portion of said face being curved concavely upward from said bottom edge with upwardly outward curvature in the lower portion merging into upwardly curvature in the upper portion of said face, said leading end edge forming a forwardly projecting point with said bottom edge and extending upward from said point first backwardly and then forwardly in a path corresponding sub-

stantially to an intersection of said curvatures by a surface fitting the side wall of the basket.

16. A discharger shoe for removing solids from a rotating centrifugal basket, comprising an elongated shoe body movable radially outward in the basket to discharge solids therefrom and carrying at a radially outward point a cutting tip acting to displace the solids upon such outward movement, and an outward facing skid fixed on said body having its face aligned laterally with said tip but spaced radially inward therefrom and forwardly therefrom in the direction of approach of solids to be discharged, to limit the cutting depth of said tip by sliding contact with part of the rotating solids.

17. A discharger shoe for removing solids from a rotating centrifugal basket, comprising an elongated shoe body carrying at a radially outward point a cutting tip acting so displace solids when moved thereinto either outward toward or axially along the basket side wall, and a skid fixed on said body having an outwardly facing surface aligned laterally with an upper portion only of said tip and spaced a predetermined radial distance inward therefrom and forwardly therefrom in the direction of approach of solids to be discharged, so that part of the rotating solids may bear against said skid to limit the cutting depth of said tip to a swath not thicker than said distance during the outward tip movement and to a swath not exceeding the tip height below said skid during the axial tip movement.

18. A discharger shoe for removing a rotating annular mass of solids from the side wall of a centrifugal basket, comprising an elongated shoe body having a forward end to be swung outward to the basket side wall and carrying at said end two laterally aligned spaced discharging tips, one of said tips being yieldably mounted to act at a greater distance from the axis of the basket than the other, an outwardly facing skid fixed on said body in laterally aligned relation to and between said tips and having its working surface disposed at a distance from such axis less than that of the yieldably mounted tip in its outermost position but always more than that of the other tip.

19. A discharger shoe for removing solids from a rotating centrifugal basket, comprising an elongated shoe body carrying at its outermost point a yieldably mounted cutting tip acting to displace the solids upon movement outward thereinto, a skid on said body having its working surface aligned laterally in front of said tip, but spaced

inwardly of the outermost position thereof, and a digging device mounted in laterally aligned relation with said cutting tip and spaced inwardly of the outermost position thereof but outwardly of said skid surface.

20. A discharger shoe for removing solids from a rotating centrifugal basket lined with a filtration screen comprising; an elongated shoe body having an inner face, a cutting tip at the leading edge of said face and a cutting edge along the bottom of said face, wherein the forward portion of said face is curved concavely upward from said cutting edge with upwardly outward curvature in the lower portion merging into upwardly inward curvature in the upper portion; a second tip normally disposed outside the other to act at a greater radial distance from the axis of the basket and being movable inward relative to said body under pressure; and a skid carried by said body between the two tips in lateral alignment therewith and having its working surface spaced radially inward from the normal position of the leading edge of the outer tip but outward of the first named tip.

21. A discharger shoe for removing solids from the side wall of a rotating centrifugal basket comprising an elongated shoe body movable axially along the basket side wall and carrying a cutting tip to displace a swath of solids upon each rotation, and a skid fixed on said body having a downwardly facing surface aligned laterally with a portion of said tip above the lower edge thereof and disposed angularly forward thereof in the direction of approach of solids to be discharged to limit the depth of the swath cut by riding on the surface of the rotating solids formed while removing a swath in the prior rotation of the basket.
